UNITED STATES PATENT OFFICE.

WILLIAM S. FRIEDLANDER, OF HOBOKEN, NEW JERSEY, ASSIGNOR TO
JACOB S. BERNHEIMER & BRO., OF NEW YORK, N. Y.

DESIGN FOR THE ORNAMENTATION OF FABRICS.

SPECIFICATION forming part of Design No. 17,880, dated November 15, 1887.

Application filed October 7, 1887. Serial No. 251,767. Term of patent 7 years.

To all whom it may concern:

Be it known that I, WILLIAM S. FRIEDLANDER, a subject of the Emperor of Germany, residing at Hoboken, in the county of Hudson and State of New Jersey, have invented and produced a new and original Design for the Ornamentation of Fabrics, of which the following is a specification, reference being had to the accompanying drawing, forming a part thereof.

The drawing represents a surface printed or otherwise provided with my newly-designed pattern.

The leading feature of my invention is the conventionalized representation of quilting upon textile or other fabrics of cotton, silk, wool, or other substance; upon mohair, woven goods, or goods composed of one or more substances; upon leather, paper, or any other suitable substance, whether flexible or not.

In the drawing, A represents a surface divided in this instance into squares *a*, the lines forming the sides of the squares running diagonally across the material, similar to quilting-stitches. These squares *a* have printed, stamped, or otherwise fixed upon their surfaces at least two colors or shades of color. One color—say the darker or stronger color—beginning at one side of a square where it is

deepest, extends with gradually-diminishing intensity over about one-half the surface thereof. The other color—say the lighter or fainter color—commencing at the opposite side, extends with gradually-diminishing intensity over the remainder, or until it reaches the first color, when it blends therewith along about the vertical diagonal of the square. The darker color may extend over a little more than one-half of the square in order to give a deeper shade to the representation. While it is generally intended to have the same colors on all the squares or quilting figures, these may differ in color, only so that each has for itself differing colors or shades of color.

I claim—

The herein-described design for the ornamentation of fabrics, consisting in the conventionalized representation of quilting in squares, each of the said squares being in different colors or shades of color, substantially as shown and described.

In testimony whereof I affix my signature in presence of two witnesses.

WILLIAM S. FRIEDLANDER.
